UNITED STATES PATENT OFFICE.

LEONARD JENNITT TODD, OF STOKE NEWINGTON, LONDON, ENGLAND.

STEAM-ENGINE.

1,239,747.

Specification of Letters Patent. Patented Sept. 11, 1917.

Application filed March 16, 1916. Serial No. 84,626.

To all whom it may concern:

Be it known that LEONARD JENNITT Todd, a subject of the King of Great Britain and Ireland, residing at 25 Brooke road, Stoke 5 Newington, London, N., England, has invented certain new and useful Improvements in Steam-Engines or the like, of which the following is a specification.

This invention refers mainly to a single 10 driving handle and mechanism connected therewith, which controls a combined shut-off and expansion and reversing gear, in such a manner as to be practically applicable to steam, compressed air, and the like.

15 As applied to steam locomotives, or other elastic fluid engines worked by a direct hand control, the invention possesses the following general features:

20 1. The operation of any such engine is made similar in simplicity and ease of manipulation, to that of an electric motor.

25 2. All variations in the power of the engine are caused by altering the rate of expansion, so that the engine is always worked with the greatest degree of expansion, and therefore of economy.

30 3. The economic working of the engine is rendered largely independent of the skill of the operating engineer.

4. This method of working is capable of effecting a great amount of economy in fuel and water.

35 Single driving handle stop-expansion and reversing mechanisms as hitherto proposed, are inapplicable to steam locomotives; on account of the great number and complexity of their working parts, and the unsatisfactory nature of their action. But all these difficulties are entirely removed by the present 40 invention.

For the purposes above named my improved control gear comprises features and arrangements fully described, by way of example, hereinafter.

45 This specification is illustrated in the accompanying six sheets of drawings, containing six figures; in which the letters and numerals of reference have the same significance throughout.

50 Figure 1 shows a general sectional, longitudinal elevation of the invention, with a single hand lever controlling a combined shut-off and expansion and reversing gear, through the medium of a power relay; as applied to a dual-exhaust cylinder.

55 Fig. 2 shows a line diagram of the valve

control gear of the invention, with the valves which admit the working fluid full-shut.

Fig. 3, shows a line diagram of the valve control gear, with the valves which admit 60 the working fluid full-open.

Fig. 4 shows a general sectional, longitudinal elevation of the invention, with a single hand lever controlling a combined shut-off and expansion and reversing gear, 65 through the medium of a power relay; as applied to an ordinary type cylinder.

Fig. 5 shows a general sectional, longitudinal elevation of the invention, with a single hand lever directly controlling a combined 70 shut-off and expansion and reversing gear; as applied to a small dual-exhaust cylinder.

Fig. 6 shows the complete valve control action, that is given by the single driving 75 handle.

In Fig. 2 the line A B represents the longitudinal center line of the engine, on which the main dual-exhaust cylinder J is placed, which has its major exhaust release at V, caused by the main piston J¹, and which has 80 its minor exhaust release at V¹ and V², caused by the ordinary piston valve P. And parallel to this first line is a second center line C D, on which is placed the valve control gear, which shuts off the working fluid, 85 and also varies the admission of the same to the cylinder J.

On the line C D are placed two control pivots marked 4 and 4— which either may or may not also form the spindles of vibrating 90 valves. And between the transverse center lines of the two pivots, that lie at right angles to the line C D, and on either side of the control line C D, is placed a variable motion joint marked 1. This has a longitudinal motion to and fro, substantially parallel to the line C D; and in a reversing engine, either in agreement with the motion of the main piston J¹, or in opposition to the same; the latter being preferable. This motion may be given by an eccentric, or other mechanism, or may be conveniently derived from the main crosshead 110, by means of the link 11, the reducing lever 12, and the rod 13.

100 The variable control joint 1, has also a transverse motion, substantially at right angles to the line C D, regulated by the lever 7 which is connected to it by the link 8. So that the joint 1 moves within the 110 limits of the contour E F G H, in a series of longitudinal paths, as may be determined

by moving the lever 7, either nearer to, or farther from the line C D. And this contour, most suitably, lies altogether on either one side or the other of the line C D, on which the two control pivots 4 and 4 are situated.

On the control pivots 4 and 4 are fitted levers 3 and 3, which, most suitably, lie on the opposite side of the line C D, to that on which the control contour E F G H is placed, and the levers are connected to the control joint 1 by the links marked 2 and 2.

The main cylinder J has a primary cut-off valve at each end, of any suitable kind, but preferably of the vibrating class, as shown at 5 and 5 in Fig. 2. According to this arrangement the control pivots 4 and 4, also form the spindles of the valves 5 and 5—but this is not necessarily the case.

These valves cut off the working fluid from the ports 6 and 6, at their outside edges; that is, at the edges of the two ports that are farthest from the central control joint 1. And this mechanism is capable of giving the following actions:

If the control joint 1 be moved close to the line C D, and consequently to the bottom of the contour, at E F, as shown in this Fig. 2:—Then the links 2 and 2 move the levers 3 and 3, so as to cause the valves 5 and 5, to entirely close the ports 6 and 6. And then the joint 1 may rock the valves 5 and 5 to and fro through the action of the rod 13; but yet they will not uncover the ports 6 and 6, by any pre-arranged minimum distance, say half-an-inch. And thus, in that position of the control joint 1, the valves 5 and 5 form an absolute shut-off gear.

Then again:—The control joint 1 might be moved from its position of “shut” to the position marked 0, on the sector of Fig. 2, which radiates from the lever 7. When the links 2 and 2 would pull the levers 3 and 3 inward, and so move the cut-off edges of the valves 5 and 5, toward the outside cut-off edges of the ports 6 and 6. And then the valves might vibrate to and fro, with their cut-off edges just coming to the cut-off edges of the ports; but without any admission of the working fluid being actually given.

Or:—The control joint 1 might be moved farther upward, so as to give the admission of 10 per cent. at the beginning of each stroke of the main piston J¹. Or, it might be moved still farther upward, so as to give 20 per cent. of admission. Or it might be moved still farther, so as to give 30 per cent., or 40, 50, 60, 70 or 80 per cent. admission. Until finally, when the control joint 1 had been moved to the extreme top of the contour at G H it would give the admission of 90 per cent. from the commencement of each stroke of the piston J¹. And

then the valve gear and the admission valves 5 and 5 would have changed to the positions shown in Fig. 3.

The contour E F G H as shown in Fig. 2 is not symmetrical in shape, and hence the joint 1 would have a movement to some extent unequal, which if uncorrected, would give an unequal admission to the two ends of the cylinder J. And in order to equalize this:—The end of the lever 7, to which the joint 1 is connected by the link 8, is caused to move in an arc marked 71, so as to alter the vibrating point of the lifting link 8, in such a way as to give the required equality of admission. And the curvature of this arc is found in a similar manner, to that employed to equalize the action of an ordinary reversing gear; that is, “points” are experimentally found, through which the required curve is then caused to pass.

And the result is that the admission at each end of the cylinder J, can be made absolutely equal, all the way from 0 to 90 per cent. And as the motion joint 1 is driven in direct opposition to the motion of the main piston J¹, this equality of action is the same, with either direction of rotation.

The primary valves 5 and 5, as controlled by the variable joint 1, and when used for hand control, thus act as a positive shut-off gear, and also give any desired variation in either the closure, or the termination of the admission of the working fluid; but they do not provide for the correct commencement of the admission to the main cylinder J. Nor do they provide for the release of the whole of the waste working fluid from an ordinary cylinder; or for the release of the residual part of the same from the dual-exhaust cylinder J; and therefore a secondary valve, or valves, must be provided to give these necessary requirements.

This secondary valve or valves, may be of any suitable kind, but is preferably a piston valve, which is marked P in Fig. 2. It is arranged to give the correct commencement of the admission of the working fluid to the main cylinder J; and also to give a suitable release to either the whole, or the residual part of the waste working fluid, as may be required.

The direction in which the crankshaft, marked 100 in Figs. 1, 4 and 5, shall turn, is determined by any suitable reversing gear, being applied to the secondary valve P; say 120 such as that shown at 120, and which is varied by a lever, or handle, marked 21.

In order to bring the action of the primary valves 5 and 5, and the action of the secondary valve P into a single lever hand control, the variable control joint 1 is connected to and adjusted by the reversing lever, or handle 21, in such a way that:—When the reversing handle stands in its central position, the variable control joint 130

1, holds the primary valves at full-shut; and when the reversing handle is moved to either full-fore or full-back gear, the control joint 1 moves the primary valves to full-open.

5 This may be accomplished by using a double-action elbow or knuckle joint, in connection with the valve control gear shown in Fig. 2. This consists of two links marked 10 L and M, which are jointed together where they meet at N; the link L being suspended from a fixed center at K, and the link M being jointed to the lifting lever 7, which is connected to the control joint 1 by the links 15 8. The reversing handle, or lever, which moves the reversing gear connected to the valve P, is shown at 21; and a rod marked 14, is carried from it to the elbow link L, as shown.

20 With this mechanism arranged as shown in Fig. 2:—When the reversing handle stands in its central position at "shut", the rod 14 holds the elbow links L and M in a straight line, so that the lifting lever 7, and 25 also the control joint 1, are held down, also in their positions of full "shut". Then, supposing the reversing lever to be moved to its full "back" position, the rod 14 will move the joint N, to the position X; when the link 30 M will draw the lifting lever 7, and the control joint 1, to their extreme height of 90 per cent. admission. And then the reversing lever 21, the elbow joint L M, the valve control gear, and the admission valves 5 and 5, 35 will occupy the positions shown in Fig. 3.

40 And the same result will be produced by moving the reversing lever to its extreme "fore" position; for then the joint N will be moved to the position of Y, which will obviously open the admission to precisely 90 per cent. as before.

45 So that by moving the reversing lever 21 either forward or backward, as may be desired, any amount of graduated admission of the working fluid can be given by the 50 valves 5 and 5, all the way from 0 to 90 per cent., and this with either direction of rotation. And by bringing the reversing lever 21 into its central position, the valves 5 and 5, are always moved back to full "shut" suppression, as shown in Fig. 2.

55 This mechanism for thus adjusting the control joint 1, and for combining the admission of the working fluid, as controlled by the lever 7, and the reversing of the engine, as controlled by the lever 21, into a single driving handle control, may be varied, provided always that:—When the reversing handle 21 stands in its central position, the 60 variable control joint 1 holds the primary valves 5 and 5 at full-shut; and when the reversing handle 21 is moved to either full-fore or full-back gear, the control joint 1 moves the primary valves 5 and 5 to full-65 open.

The valve control joint 1 may have its "shut" position either at E F, near to the control line C D; or at G H, at the farthest distance from the control line. It is however better to have the "shut" position near 70 to the line C D, as shown in Fig. 2. As then, when the joint 1 is moved away from E F, the control gear at first gives but little motion to the levers 3 and 3; which makes a relatively long distance from the full "shut" 75 position, to the commencement of the 0 per cent. admission, as shown on the sector of Fig. 2, which radiates from the lever 7. And it also causes the distances between the percentages of admission to be greater at 80 the early stages, and to be gradually reduced as the extreme of 90 per cent. admission is approached.

This considerable distance from "shut" to the 0 position of admission, is further increased by the action of the elbow links L and M; so that when this action comes to be transferred to the lever 21, by means of the rod 14, it may be seen that this reversing lever 21, moves through about one-half of 90 its distance, from its central position of "shut" before the 0 position of admission is reached, on its way to either "fore" or "back" full gear.

The object in having the reversing lever 95 21 to move about one-half of its travel, from its central position, before the 0 position of admission is reached, and the valves 5 and 5 commence to open is:—That the piston valve P may then have its minor exhaust release 100 moved over to full gear, before the admission by the valves 5 and 5 commences. With the consequence that the minor exhaust-release by the valve P, never takes place earlier than the major exhaust-release by 105 the main piston J¹, while the working fluid is being admitted by the valves 5 and 5. Also, the compression of the residual waste working fluid, is then always moderate in amount. And in addition, the piston valve 110 of a dual-exhaust cylinder, can then be made very small in diameter, as herein afterward further explained.

These features of the steam distribution are illustrated in Fig. 6, by the percentages 115 radiating in a sector from the lever 21, which shows the variations of action that are produced by simply moving the single driving handle to and fro, from its central position of "shut", to either the fore or back full 120 gear, as may be desired.

The first row of these percentages marked R, shows the varying admissions of the working fluid, produced by the primary valves 5 and 5.

The second row marked S, shows the corresponding admissions, which at the same times are given by the secondary piston valve P.

The third row marked T shows the earli- 130

est openings of the exhaust-release, during the whole period of admission, from 0 to 90 per cent. The release shown of 90 per cent. is the major exhaust-release, caused by 5 the main piston at V; the minor exhaust-release, caused by the valve P, at V^1 and V^1 , being always later than this 90 per cent. And so this minor exhaust-release by the piston valve P, always remains in full open 10 gear, however the ratio of expansion may be varied; and is automatically prevented from giving an earlier release during the admission of the working fluid, than the major exhaust-release caused by the main piston 15 at V.

And the fourth row marked U, shows the moderate compressions of the unescaped waste working fluid, caused by the closing of the minor exhaust-release at V^1 and V^1 . 20 As the admission gear and the reversing gear are positively connected, these two gears cannot get out of "step" with each other, when the single control handle is used to give counter-admission, in order to facilitate braking, sudden stoppage, or very quick 25 reversal. And also the engine cannot then be readily started in an un-desired direction; as may easily be done when the admission gear, and the reversing gear, are worked by 30 separate handles.

In a large or medium engine as shown in Fig. 1, the single lever 21, which controls the primary admission valves and the secondary reversing valve, may be moved by a 35 power relay cylinder marked 25, worked by a small driving handle 26; which handle may be moved by a small quick-pitch screw, if so desired. Or the lever 21 may be moved directly by an ordinary screw reversing motion.

In a small engine, as shown in Fig. 5, the single control lever 21 may be moved directly by a hand lever 27; which will then also give the variations of action, that have 45 been detailed.

The said control gear, as applied to a dual-exhaust cylinder J, possesses the following advantages over its application to an ordinary cylinder Q:—

- 50 A much smaller piston valve.
- A much smaller waste clearance.
- A greatly increased ratio of expansion.
- A much larger exhaust-release area.
- A much larger indicator diagram.
- 55 A greatly increased effective power.
- A much greater efficiency.

And the said invention enables the economy of the simple expansion, superheating locomotive, or like engine, to be carried far 60 beyond that of ordinary locomotive practice.

It also enables the economy of the saturated steam locomotive, or like engine, to be carried much further than is at present possible with such engines.

65 It also enables the hot-water fireless loco-

motive to run much farther than it can do at present.

And it also enables the compressed air locomotive or like engine, to run with much greater efficiency, than this class of motor at 70 present shows.

The invention is applicable to engines which use steam, compressed air, or other elastic fluid; with either a simple expansion or other expansive system of cylinders. 75

The invention has been described hitherto as applicable to double-acting engines, but it is equally applicable to single-acting engines by merely omitting one of the pivots marked 4, and the lever, link, and valve connected therewith. 80

The numerical figures given in this specification, or shown in the accompanying drawings, in respect to percentages of admission, expansion, release, compression, or 85 having reference to other features, are merely illustrative, and may be varied.

What I claim and desire to secure by Letters Patent is:—

1. A steam or other elastic fluid engine 90 comprising the elements of a combined shut-off and expansion gear including primary expansion valves, a secondary admitting and exhausting valve adapted to receive working fluid from the primary valves, a main driving dual-exhaust cylinder adapted to receive working fluid from the secondary valve, a reversing gear connected to the secondary valve and a single controlling handle connected to the primary expansion 100 valves, and also to the reversing gear of the secondary valve, the whole being correlated to give a single handle control of the shut-off and expansion of the working fluid by the primary valves, and of the direction of 105 the rotation of the engine by the secondary valve.

2. A steam or other elastic fluid engine comprising the elements of a primary shut-off and expansion gear including two pivotal 110 axes, a variable control driving joint located between the transverse center lines of the axes that lie at right angles to a line connecting the said axes, driving levers oscillating about the said axes, diagonal driving 115 links connecting the said levers with the variable control driving joint, primary shut-off and expansion valves connected either directly or indirectly to the said pivotal axes, a secondary valve adapted to receive 120 working fluid from the primary valves, a main driving cylinder adapted to receive the working fluid from the secondary valve, a reversing gear connected to the secondary valve, and a single controlling handle connected to the variable control joint of the primary valves, and also to the reversing gear of the secondary valve, the whole being correlated to give a single handle control 125 of the shut-off and expansion of the work- 130

ing fluid by the primary valves, and of the direction of the rotation of the engine by the secondary valve.

3. A steam or other elastic fluid engine 5 comprising the elements of a primary shut-off and expansion gear including two pivotal axes, a variable control driving joint located between the transverse center lines of the axes that lie at right angles to a line connecting the said axes, driving levers oscillating about the said axes, diagonal driving links connecting the said levers with the variable control driving joint, primary shut-off and expansion valves connected either 10 directly or indirectly to the said pivotal axes, a secondary admitting and exhausting valve adapted to receive working fluid from the primary valves, a main driving dual-exhaust cylinder adapted to receive the 15 working fluid from the secondary valve, a reversing gear connected to the secondary valve, and a single controlling handle connected to the variable control joint of the primary valves, and also to the reversing 20 gear of the secondary valve, the whole being 25 correlated to give a single handle control of

the shut-off and expansion of the working fluid by the primary valves, and of the direction of the rotation of the engine by the secondary valve.

- 30 4. A steam or other elastic fluid engine comprising the elements of a primary expansion gear including two pivotal axes, a variable control driving joint located between the transverse center lines of the axes 35 that lie at right angles to a line connecting the said axes, diagonal driving links connecting the said levers with the control driving joint, primary expansion valves connected to the said pivotal axes, a secondary 40 admitting and exhausting valve, adapted to receive working fluid from the primary valves, and a main driving dual-exhaust cylinder adapted to receive the working fluid from the secondary valve, the whole 45 being correlated to control the working fluid by means of the primary valves, by means of the secondary valve, and by means of the dual-exhaust cylinder main piston.

50 In testimony whereof I have affixed my signature.

LEONARD JENNETT TODD.
